CARRIAGE TRAVERSING MECHANISM

Wilfred H. Howe, Winchester, Mass., assignor to
The Cincinnati Milling Machine Co., Cincinnati,
Ohio, a corporation of Ohio

Application May 16, 1933, Serial No. 671,362

9 Claims. (Cl. 172—240)

This invention relates to electric mechanism for producing traversing motions of a traversing carriage, such, for example, as the work table of a universal grinder or similar machines, although it should be understood that it is not limited to any particular type of mechanism. It is more particularly suitable for light, slow speed service which involves certain special difficulties. Heretofore it has usually been found necessary to employ some type of "load and fire mechanism" in such service in order to insure reversal of the traversing motor after its motion in one direction has been stopped, as by the contact of the carriage with a switch opening dog, there being too little over-travel of the carriage after the motor switch has been opened to insure closing of the motor connections for reverse carriage travel.

In accordance with the present invention no "load and fire mechanism" is necessary, closing of a switch at one end of the carriage traverse and opening the switch at the other end of its travel serving to open and reverse the motor connections. An automatic time delay mechanism for cutting down the energy supplied to the motor for a predetermined time after reversal is employed to prevent unduly heavy motor stopping and starting current and to control the motion of the carriage to effect a dwell at the traverse limits and to control its deceleration and acceleration adjacent thereto.

Means may also be provided according to this invention for increasing the motor field strength at the lower speeds of carriage travel, which improves the speed regulation under varying loads.

For a more complete understanding of this invention, reference may be had to the accompanying drawings, of which,—

Figure 1 is a diagram of a feed motor control mechanism embodying this invention.

Figure 2 is a front elevation of a grinding machine to which the mechanism may be applied.

Figure 3 is a detail section through the housing for the traversing motor.

Figure 4 is a detail section transverse to the section of Figure 3 and showing part of the driving connection from the traversing motor to the table.

Figure 5 is a detail section to a larger scale on line 5—5 of Figure 2.

Figure 6 is a detail section on line 6—6 of Figure 5.

Referring to Figure 1 of the drawings, at 1 is shown a universal reversible motor which may be connected by any suitable means to drive a

reciprocating carriage or table as is well known in the art. At 2 is shown a single-pole single-throw switch, which is preferably of the mercury type, so arranged as to close a circuit when tipped in one direction and to open the circuit when tipped in the opposite direction. As shown this switch is provided with an actuating arm 3 which may be struck at suitable times by dogs 4 and 5 on the traversing carriage, thereby to tip the switch alternately in opposite directions to open and close the circuit controlled thereby at opposite limits of motion of the traversing carriage in a manner well known in the art. This switch 2 controls a circuit, deriving its energy as from an auto-transformer indicated generally 6, in which circuit is interposed the energizing coil 7 of a double-pole double-throw relay 8 so that when the switch 2 is closed, as in the position shown in the drawings, this relay is energized to close contacts at a and b and c and d, respectively. Current passes from the transformer tap 100 through the line 101 to the switch 2, thence through the lead 102, through the coil 7 and through the lead 103 to the transformer tap 104. In the connections as shown, the in-put leads 20 and 21 also connect directly to the leads 103 and 101, respectively, but the lead 21 may be connected to other transformer taps 100a, 100b or 100c to thereby vary the voltage impressed on the motor. When the switch 2 is in open position this relay 8 is de-energized and the contacts a, b and c, d are opened and the contacts e, f and g, h are closed. The contacts a, b and e, f control the connections to the reverse motor field windings 10 and 11 of the motor 1, thus to control the direction of rotation of this motor, so that when the switch 2 is closed the motor is energized to move the carriage in a direction to bring the dog 4 toward the arm 3, which at the end of this traverse will act to move the arm 3 to the right to an extent sufficient to open the switch 2, whereupon the field coil 10 of the motor is de-energized and the field coil 11 becomes energized so that the motor reverses and the carriage is moved in the opposite direction. The field coils 10 and 11 have the common lead 105, which also is connected to one side of the motor armature M. Means are provided for preventing an undue rush of current when each reversal takes place and to control the deceleration and acceleration of the motor and produce a dwell at the end of the stroke as will later be described.

The motor 1 as shown in this figure derives its energy from the auto-transformer 6 through a selective transformer tap switch indicated gen- 55

erally at 15. The selective transformer tap switch 15 leads to one side of the motor through the lead 106, thence through the lead 105 to the common point of the field coils 10 and 11. Dependent upon the position of the switch 8, current passes through one or the other of these field coils, leads 10a or 11a and contacts a, b or e, f, through the lead 107 to the lead 103 and the transformer tap 104. As shown this switch 10 15 is in position to make connection with the transformer tap k, the taps k and l of the transformer being of relatively low voltage, while the taps m and n are higher voltage taps. When either of the lower voltage taps k and l are connected some or all of the resistance 16 is inserted in parallel with the armature circuit of the motor 1 through the lead 105. This lowers the effective resistance of the armature circuit and thus tends to increase the total current flow, 20 but since the total current passes through the field winding, this in effect increases the field current at the lower speeds, which tends to increase the field strength and improves the speed regulation under varying load, and also somewhat increases the acceleration of the motor after each reversal. The lower the voltage, the smaller is the value of the resistance thus inserted to correspondingly increase the field strength.

30 In order to prevent excessive current flow to the motor 1 at each reversal and to provide desirable speed control of the carriage, provision is made for automatically decreasing the energy supplied to the motor for a definite predetermined time after each reversal. This as shown is done by introducing a resistor 25 in the motor circuit 1, this resistance being arranged to be short circuited after a predetermined time after each reversal of the connections to the motor 1.

40 The short circuiting mechanism is connected at opposite ends at either end of the resistance 25 at the points x and y through the leads 108 and the leads 103 and 109. It includes therein in parallel normally closed relay-actuated switches 45 26 and 27 between the leads 108 and 109 which switches are arranged to be opened on energization of their respective relay coils 28 and 29. These relay coils 28 and 29 are arranged in series with each other and also in series with a pair of 50 inductances 30 and 31, and the circuit including the two inductances 30 and 31, and both the relay coils 28 and 29, is fed direct current from any suitable source as by means of the rectifying tube 33 receiving energy from the transformer 6.

55 This tube as shown is of the two-plate type, one plate being connected to one end of the main winding of the auto-transformer 6 through lead 110 and the other being connected to the alternating current power supply line 21 through the lead 101. The filament of this tube is energized through the coil 34 of the auto-transformer and direct filament-plate current smoothed out by the filter system comprising the condensers 35, the choke 36, and the resistance 37 is fed through lead 111 to one side of the circuit comprising the inductances 30 and 31 and the relay coils 28 and 29, the return being back through lead 109 to the mid-point of the auto-transformer through the point y. Either one or the other of the relay coils 28 or 29, together with its companion inductance 30 or 31, is arranged to be short circuited so as to form a closed circuit path including both, on reversal of the motor whereupon the inductance in the short circuited portion continues to force current through the companion

relay coil 28 or 29 for a certain length of time before this current dies out. When this current dies out the relay will release its switch and short circuit the resistance 25 therethrough. The short circuiting of these delay circuits, each 5 of which includes an inductance and its connection relay 28 or 29, is produced by closing the contacts at c, d or g, h of the relay 8. Closing contacts c, d connect the line 112 leading from one side of the relay 28 to the lead 111 through the inductance 30 and lead 114 to the opposite side of the relay 28. Similarly closing of contacts g, h connects lead 112 from one side of the relay 29 to lead 109 through inductance 31 and lead 115 to the opposite end of the relay 29. 15 Thus when the carriage has reached that end of its traverse where the switch 2 is thrown to energize the relay coils 7, contact is made between c and d. This acts to short circuit the delay system comprising the inductance 30 and the relay coil 28 and when the current in this short circuited delay system falls to a certain extent the switch 26 springs closed, thus short circuiting the resistance 25 and interposing the full voltage as determined by the setting of the switch 15 25 on the carriage actuating motor. When the carriage reaches its other limit of motion and trips the switch 2 to de-energize the relay coil 7, the contacts a, b are opened and the contacts e, f are closed, thus reversing the motor connections and at the same time the contacts c, d are opened and the contacts g, h are closed. The opening of the contacts c, d opens the short circuit of the resistance 25 through the switch 26 and the closing of the contacts g, h short circuits 35 the delay system including the inductance 31 and the relay coil 29 and after the current in this short circuited delay system dies down sufficiently the switch 27 closes and short circuits the resistance 25. In each position of the relay 40 8, the rectifier tube continues to feed direct current through the inductance and the delay action relay coil which are not short circuited. The length of time that the resistance 25 remains 45 actively interposed in the motor circuit may be adjusted independently at each end of the carriage traverse by the setting of the variable resistances 43 and 44 which are connected across the inductances 30 and 31. It will be noted that this delay mechanism is controlled by electrically 50 responsive means so that it requires only very simple elements. Not only does this resistance 25 act to prevent an undue rush of current at the instant the motor connections are reversed, but it also effects a dwell at the ends of the carriage stroke and produces a gradual deceleration and then a gradual acceleration before and after the dwell, these rates, as well as the length of the dwell, being adjustable independently at opposite ends of the carriage stroke by varying the 55 resistances 43 and 44.

60 Figures 2 to 6, inclusive, show the application of this invention to a grinding machine. Referring to these figures at 50 is shown the carriage of a grinding machine supported for axial travel 65 on the bed 51. This carriage is shown as supporting a head stock 52 at one end and a tail stock 53 at the opposite end, these stocks being adjustable from and toward each other to suit the length of the work, as is well understood. 70 The head stock is shown as provided with a live center 54 and the tail stock with a dead center 55 between which work to be ground is placed. At 56 is shown a stationary stand for rotatably supporting a grinding wheel 57 past which the 75

work is traversed by the traverse of the carriage 50. As shown, this carriage 50 is provided on its under face with a rack bar 60 with which meshes a suitable pinion (not shown) on a traversing shaft 61 (see Figure 4). This traversing shaft is connected through a train of gearing indicated generally at 62 to the motor 1 to be driven thereby.

In Figures 3 and 4 this motor 1 is shown as mounted in a suitable frame housing 65 and on the end of its armature shaft 66 to which is secured a gear 67 forming a part of the gear train 62 is secured a metallic disk 70 for rotation in its plane by rotation of the shaft 66. Preferably this disk is of copper or aluminum and it is rigidly attached to the armature shaft 66 so as to rotate therewith. This disk extends between the poles 71 of an electromagnet 72 and this electromagnet is energized by direct current, which, as shown in Figure 1, may be obtained from the rectifier system including the rectifier tube 33 and which is shown as employed to energize the delay relay coils 28 and 29 and the inductances 30 and 31. The coil 73 of the electromagnet 72 may be connected as shown in Figure 1 to the lead 103, a variable resistance 74 being employed in series therewith and connecting to the lead 113 extending to the filament of the tube 33 so as to control the amount of current flow through the coil 73. Electric current flow in the disk induced by rotation of the disk between the poles of magnet produces a reactive force tending to oppose the rotation of the disk. This opposing force is proportional to the speed of rotation of the motor within quite wide limits of speed of rotation. It thus acts as a brake tending to cause the motor to operate at a constant speed. Since the torque of the motor varies inversely with its speed while the retarding torque of this brake varies directly with the speed, at a certain speed the driving and retarding forces will be equal leaving no energy for acceleration or deceleration of the motor. Further, the acceleration of the motor immediately after it starts will be more rapid than were a frictional brake employed, since at lower speeds the retarding torque is materially reduced over that at full speed. The use of this brake instead of relying on frictional loss and output power as limits to motor speed has several advantages. The motor has a lower maximum speed and is thus more quiet and has less wear. Frictional losses are variable, particularly in case a considerable part of the friction is in an oil immersed gear train, in which resistance varies with temperature, while the disk brake is not subject to the effects of these variables. Furthermore, by supplying the motor and the brake from the same electrical power source, both driving and retarding torque will vary directly with voltage, this resulting in negligible speed variations of the motor from this cause. Further, there is no mechanical contact between moving parts involved with this disk brake so that there is nothing to wear or deteriorate.

It should be understood, however, that the carriage traversing mechanism may operate without using such a brake if this is desired, it being no way essential to the effectiveness of the reverse mechanism per se.

Figures 5 and 6 illustrate a mounting for the mercury switch 2, as shown it being carried by a rock shaft 80 which carries on its inner end a lever 81 provided with contact elements 82 at opposite ends. This rock shaft 80 is normally held in an inward position by means of a spring

83 surrounding a reduced portion 84 thereof and seated in a socket 85 in the carriage 50. In this inward position the contact elements 82 are in position to impinge upon the inclined faces 87 of the dogs 4 and 5 at either end of the stroke of the table, thus to cause making or breaking of the circuit through the switch 2 as has been previously described. To the outer end of the rock shaft 80 is secured a handle 90 which may be grasped and the rock shaft pulled outwardly 10 against the pressure of the spring 85, so as to bring the elements 82 out of operative position, and a screw 91 may then be tightened to hold the shaft 80 in this inoperative position. This screw 91 may also be adjusted to impart a controlled 15 frictional resistance to the rocking of the shaft 80. The handle 90 also makes possible hand actuation of the switch 2 without reference to the dogs 4 and 5 in case at any time it should be desired to reverse the direction of motion of the 20 table intermediate its normal limits of reciprocation.

It will be noted that the usual load and fire mechanism is unnecessary in a machine provided with this invention for several reasons. The reversal of the direction of motion is controlled by the making and breaking of a single contact and there is no effect whatever until this contact has either been made or broken to reverse the direction of driving. Even the merest trace of over 30 travel, which always occurs in measurable amount, serves to ensure the hold of the mercury and point contact in either make or break position. Moreover, a mercury switch as ordinarily made has inherently a tendency to stay in the 35 position of make or break in which it is positioned at any time as, due to liquid friction and surface adhesion, the mercury does not flow until the switch tube has perceptibly passed the center point. Likewise also the tubes are commonly made with a slight curvature which acts to prevent return flow until the switch tube has passed the control point in the opposite direction. There is also sufficient friction in the rock mechanism so that there is no tendency to rock 40 the switch except as this is accompanied by the action of the dogs 4 and 5 or by the manual rocking of the handle 90.

From the foregoing description of an embodiment of this invention it should be evident to those skilled in the art that various changes and modifications might be made without departing from the spirit or scope of this invention as defined by the appended claims.

I claim:

1. A traversing carriage actuating mechanism comprising a reversible electric carriage-driving motor, means for reversing said motor at each end of the carriage traverse, means for automatically reducing the supply of energy to said motor at each reversal for a predetermined period, and means for independently adjusting the length of said period at opposite ends of the carriage traverse.

2. A traversing carriage actuating mechanism comprising a reversible electric carriage-driving motor, a relay normally connecting said motor for one direction of motion and when energized establishing reverse direction motor connections, a switch in operative relation to said carriage to be closed at one end of said carriage traverse and opened at the other end of said carriage traverse for controlling the energization of said relay, and means for operatively interposing and maintaining for a predetermined time a resistance in the

motor circuit at each reversal of motor connections.

3. A traversing carriage actuating mechanism comprising a reversible electric carriage-driving motor, a relay normally connecting said motor for one direction of motion and when energized establishing reverse direction motor connections, a switch in operative relation to said carriage to be closed at one end of said carriage traverse and opened at the other end of said carriage traverse for controlling the energization of said relay, a resistance in the motor circuit, and means acting a predetermined time after each reversal of said motor connections for short circuiting said resistance.

4. A traversing carriage actuating mechanism comprising a reversible electric carriage-driving motor, a relay normally connecting said motor for one direction of motion and when energized establishing reverse direction motor connections, a switch in operative relation to said carriage to be closed at one end of said carriage traverse and opened at the other end of said carriage traverse for controlling the energization of said relay, a resistance in the motor circuit, a connection normally short circuiting said resistance, a relay when energized interrupting said connection, an inductance in series with said connection relay, a source of direct current for energizing said connection relay, and means actuated at the end of a carriage traverse for short circuiting said connection relay and inductance.

5. A traversing carriage actuating mechanism comprising a reversible electric carriage driving motor, a relay normally connecting said motor for one direction of motion and when energized establishing reverse direction motor connections, a switch in operative relation to said carriage to be closed at one end of said carriage traverse and opened at the other end of said carriage traverse for controlling the energization of said relay, a resistance in the motor circuit, a pair of connections each normally short circuiting said resistance, a relay for each connection when energized interrupting its connection, an inductance in series with each connection relay, and a source of direct current for energizing said connection relays, said motor relay when energized short circuiting one of said connecting relays and its inductance and when de-energized short circuiting the other of said connection relays and its inductance.

6. A traversing carriage actuating mechanism comprising a reversible electric carriage driving

motor, a relay normally connecting said motor for one direction of motion and when energized establishing reverse direction motor connections, a switch in operative relation to said carriage to be closed at one end of said carriage traverse and opened at the other end of said carriage traverse for controlling the energization of said relay, a resistance in the motor circuit, a pair of connections each normally short circuiting said resistance, a relay for each connection when energized interrupting said connection, an inductance in series with each connection relay, a source of direct current for energizing said connection relays, said motor relay when energized short circuiting one of said connecting relays and its inductance and when de-energized short circuiting the other of said connection relays and its inductance, and a variable resistance arranged in parallel with each inductance.

7. A traversing carriage actuating mechanism comprising a reversible electric carriage-driving motor, a relay normally connecting said motor for one direction of motion and when energized establishing reversed motion connections, a rockable mercury switch carried by said carriage and controlling the energization of said relay, stationary dogs and cooperating elements on said carriage for effecting rocking of said switch to open or close connections to said relay at opposite ends of traverse of said carriage, a rock shaft for carrying said switch, means for yieldingly holding said rock shaft in axial position with said elements operatively related to said dogs, and means actuatable to move said shaft axially from said position against the pressure of said yieldingly holding means.

8. A traversing carriage actuating mechanism comprising a series motor, a source of energy for driving said motor, connections driven by said motor for traversing said carriage, a metallic disk connected for rotation in its plane by said motor, an electromagnet having spaced poles between which said disk extends, and a direct current supply for energizing said electromagnet.

9. A traversing carriage actuating mechanism comprising a series motor, a source of energy for driving said motor, connections driven by said motor for traversing said carriage, a metallic disk connected for rotation in its plane by said motor, an electromagnet having spaced portions between which said disk extends, and a direct current supply derived from said source for energizing said electromagnet.

WILFRED H. HOWE.
